CLAIM

The ornamental design for a power saw guide, substantially as shown and described.

DESCRIPTION

FIG. 1 is a perspective view of the power saw guide showing my new design in use;

FIG. 2 is a side elevational view thereof taken from the right side;

FIG. 3 is a top plan view thereof; and

FIG. 4 is a bottom plan view thereof.

The broken lines are shown for illustrative purposes only.

FIG. 1

FIG. 2

FIG. 3

FIG. 4
